UNITED STATES PATENT OFFICE.

EDWARD LANCASTER BURNE, OF WESTMINSTER, LONDON, ENGLAND.

MEANS FOR REGULATING THE SPEED OF WIND MOTORS.

1,403,069.

Specification of Letters Patent. Patented Jan. 10, 1922.

Application filed August 12, 1921. Serial No. 491,833.

To all whom it may concern:

Be it known that I, EDWARD LANCASTER BURNE, of 28 Victoria Street, Westminster, London, S. W. 1, England, a subject of the 5 King of Great Britain and Ireland, have invented certain new and useful Improvements in or Relating to Means for Regulating the Speed of Wind Motors, (for which I have filed applications in England March 10 31st, 1920,) of which the following is a specification.

This invention relates to automatic means for controlling the speed of windmotors.

The object of this invention is to provide 15 means for automatically controlling the speed of windmotors in such a manner that the speed will not be affected by varying wind conditions.

The drawings filed herewith show one 20 form of apparatus made in accordance with this invention in which:—

Fig. 1 is a front elevation of one of the windmotor vanes.

Fig. 2 is an end view of the inner end of 25 one of the vanes showing the components of the vanes in the normal position.

Fig. 3 is a similar view showing a typical position of the components during the governing action.

30 Fig. 4 is a similar view showing the components of the vanes furled.

Fig. 5 is a side elevation of the apparatus showing one form of governing mechanism.

Fig. 6 is a view of an alternative governing 35 mechanism.

Fig. 7 shows an alternative method of transmitting the motion of the vane components to the governing mechanism.

Fig. 8 shows yet another alternative 40 method of transmitting the motion of the vane components to the governing mechanism.

The windmotor may be provided with any 45 suitable number of vanes, one of which is shown in Fig. 1. The vane is divided in the direction of its radial length into two components, one of which I term the leading component *a* and the other the trailing component *b*, these two components being pivoted in any suitable manner to a supporting 50 radial arm *c* disposed between them.

The leading component *a* is pivoted at or near the line of its back edge and the trailing component *b* is pivoted at or near the 55 line of its front edge by any suitable method (such as hinges *d* attached to the com-

ponents *a* and *b* and to the supporting arm *c*) in such a manner that the component parts of the vane can move in the same relation to each other as the flaps of a hinge. 60 Obviously the vane components might be hinged in front of or behind the said arm instead of on either side. Instead of being supported by a radial arm as shown the components might be mounted between concentric rings bounding their inner and outer extremities and forming part of the framework of a windmotor wheel, and the vane components provided with pivots at their extremities, the pivots working in sockets 65 in the said rings. Further the relative widths and the shape of the vane components may be varied; for example, the leading component might be as wide or wider than the following component and one or 70 both components might be wider at the outer than at the inner extremity, or they might be parallel throughout their length.

When the vane is in a working position the two components are set at suitable angles for receiving the impulse of the wind. 75 This position is shown in Fig. 2.

I impart a twist to the surface of the following component of the vane so that the angle, with the plane of rotation, increases 80 as the axis of the windmotor is approached, but I prefer to make the leading component a plane surface with a uniform inclination equal to the greatest angle of the following component, i. e. when the latter is in normal 85 working position, upon the principles known to millwrights.

Referring to Figs. 2 and 5, two links *d* and *e* are secured to the components *a* and *b* or to an extension carried thereby, the 90 other ends of said links being attached to an eye bolt *f*, the connections being made by pin joints. The eye bolt *f* passes through the end of an arm *g*, the said arm being secured to a rod *h* at right angles to it. This 95 rod *h* passes axially through the hollow main shaft *j* of the windmotor.

In applying my invention to govern the speed of windmotors, I cause the two components of the vane to fold back from the 100 wind to the extent required so that the angle of the leading component of the vane, with the plane of rotation, tends to diminish and even become a negative angle, whilst the 105 angle, or angles if the surface is helical, of the following component increase and tend to approximate to a right angle to the plane 110

of rotation and to take up a position more or less parallel to the direction of the wind, as is indicated in Figure 3. I arrange that the leading component may not too quickly attain a negative angle.

In order that the angular movement of the component parts of the vane and consequently the speed regulation of the windmotor shall be automatic I oppose the tendency 10 of the wind pressure to fold back the components of the vanes by the resistance of an adjustable spring or weight. One method of carrying out this invention is shown in Fig. 5. The rod *h* is provided with a rack *h* which engages a pinion *m* mounted on a shaft *n*. Mounted on the shaft *n* is a drum *o* about which is wound a chain *p* provided with a weight *q*. Instead of the weight *q* a tension 15 spring may be employed. The chain and weight tend to rotate the drum thereby causing movement of the rod *h* which transmits the motion to the vane components. Instead 20 of the spring or weight operating on a chain a bell crank lever may be employed one arm 25 of which is adapted to coact with the spring or weight and the other arm being provided with a forked end engaging a grooved collar mounted on the rod *h*.

If desired the resistance to the folding 30 back of the vane components may be furnished by a centrifugal or other governor. One way by which this may be accomplished is shown in Fig. 6 in which the main shaft *j* carries a spur wheel *r* which drives a spur 35 wheel *s* mounted on the shaft of a centrifugal governor *t*. A sliding collar *u* is mounted on the governor shaft provided with a circumferential groove. The rod *h* also carries a similar collar *v*. An arm *w* forked at 40 its extremities coacts with the collars *u* and *v* and is pivoted at a suitable intermediate point *x*. Thus an increase of speed of the windmotor will cause movement of the collar *u* on the governor shaft which in turn 45 will move the rod *h* and tend to fold back the vane components. The centrifugal governor may be used either with or without the rack and pinion mechanism described with reference to Fig. 5.

50 The resistance to the folding back of the components may also be furnished by an increase in load on the windmotor brought about by an increase in speed.

One way in which this may be done, assuming the windmotor to be driving a dynamo, is to mount a driving wheel on the main shaft of the windmotor so as to be free to rotate thereon; the motion of the shaft is transmitted to the driving wheel through 55 some elastic medium such as a spring device. An increase of load due to an increase of speed (e. g. the greater output of a dynamo) would cause a relative movement to take place between the driving shaft and the 60 wheel (in fact a kind of "lag") which move- 65

ment or lag could be employed to adjust the angles of the components of the vanes. Thus it will be seen that the angles of the vane could be adjusted by the load instead of by the force of the wind, or again by a combination of both agencies. 70

Instead of the method of transmitting the resistance of the spring or weight or governor to the vane components described with reference to Figs. 5 and 6, I may employ the alternative method shown in Fig. 7 which shows pinions 2, 2 mounted on the axial line upon which each component turns, the said pinions operating racks 3, 3 which are connected to the rod *h* coacting with a spring 75 weight or governor as above described. 80

In operation if the wind pressure exceeds in effect that of the spring or weight it will force back the components *a* and *b* of the vanes causing them to turn on their hinges 85 thereby drawing back the links *d* and *e* and with them the eye bolt *f*, the arm *g* and the rod *h* overcoming the outward thrust due to the spring or weight. When the wind pressure diminishes to an effect below that 90 due to that of the spring or weight acting on the rod *h*, a reverse action takes place and the vane components resume their normal angles. 95

Each vane in the windmotor has an arm 95 corresponding to *g*, or, if preferred, a ring may take the place of the several arms, the said ring being connected to the rod *h* by two or more spokes.

In order that each vane may to some extent regulate independently I insert a spiral or other suitable spring 4 between the end of the eye bolt *f* and the arm *g* which allows the wind pressure to fold back the component parts of the vane to a limited extent without 105 forcing back the rod *h* and affecting the movement of the vanes collectively.

Obviously the links *d* and *e* may, if desired, be arranged so as to be in compression instead of in tension and the rod *h* so as to be 110 in tension instead of compression with the pressure of the spring or weight arranged to draw it inwards instead of pushing it outwards.

Obviously the links *d* and *e* might be 115 behind the components instead of in front. This alternative form of construction is shown in Fig. 8. Instead of a rod passing through a hollow main shaft a collar 5, provided with a circumferential groove 6, 120 is slidably mounted on the main shaft of the windmotor between the main bearing 7 and the vanes. In this case the eye bolts *f* are connected to the collar 5 by rods 8. A bell crank lever 9, pivoted at 10, is provided with 125 a forked arm 11 engaging with the groove 6 in the collar 5. The other arm 12 of the bell crank lever is the medium by which the resistance of a weight spring or governor 130 is applied.

When it is desired to stop the windmotor the vanes may be furled by releasing the spring or weight acting on the rod *h* and allowing them to fall back, so that their surfaces assume a position more or less parallel with the direction of the wind with their edges presented to it.

If desired, automatic regulation may be suspended and the angles of the vanes adjusted and fixed to suit the prevailing conditions.

In vanes of large size I may divide the component portions into two or more components in the direction of their length; each longitudinal component being independently supported by hinging to a radial arm common to all the components or by pivoting each component between concentric rings bounding their inner and outer extremities; the whole forming a complete vane; the angles of the several components of the vane being regulated, either independently or collectively, substantially in the same manner as that described for vanes of two components only.

What I claim and desire to secure by Letters Patent is:—

1. In windmotors, a vane composed of two longitudinal components, namely a leading and a following portion, the leading portion under normal working conditions be-

ing inclined at a salient angle to the following portion of the vane, the angle varying from the tip towards the inner extremity, and means for automatically moving a portion 35 of the vanes to a less effective position and later the leading portion into a position tending to produce backward rotation of the vanes.

2. In windmotors of the character claimed 40 in claim 1, radial axes having the vanes mounted thereon both portions of which are adapted to be folded back by the action of the wind against a predetermined pressure and to be returned to their normal position. 45

3. A windmotor of the character claimed in claim 1, means for moving a portion of the vanes comprising a rod running through the hollow main shaft on which the vanes are mounted, members carried by said rod, 50 connecting links adapted to connect said members to said portion of the vanes and adjustable means acting on said rod.

4. In windmotors of the character claimed in claim 1, means for adjusting the angle of 55 the portions of the vanes, and means for maintaining a constant speed under varying loads of the driven member.

In testimony whereof I have signed my name to this specification.

EDWARD LANCASTER BURNE.
